United States Patent Office

Des. 204,756
Patented May 17, 1966

204,756

AIR PURIFYING UNIT

John Farrell, 5320 Beverly Hill Lane, Houston, Tex.

Filed Jan. 25, 1965, Ser. No. 83,550

Term of patent 14 years

(Cl. D16—2)

FIGURE 1 is a top plan view of an air purifying unit showing my new design;

FIGURE 2 is a side elevational view; and

FIGURE 3 is a bottom view thereof.

I claim:

The ornamental design for air purifying unit, as shown.
